UNITED STATES PATENT OFFICE.

WILLIAM E. WHITE, OF CHICAGO, ILLINOIS.

FORM-SUPPORTING DEVICE.

Application filed December 23, 1921. Serial No. 524,445.

To all whom it may concern:

Be it known that I, WILLIAM E. WHITE, a citizen of the United States, and resident of Chicago, in the county of Cook and State 5 of Illinois, have invented certain new and useful Improvements in a Form-Supporting Device, of which the following is a specification.

My invention relates to devices for supporting concrete forms and particularly to a much simplified construction having certain functions and advantages which will be set out hereinafter.

One of the objects of my invention is, as 15 stated, to materially simplify the construction and operation of devices of this character. One of the specific objects is to provide a construction in which substantially all the parts thereof may be removed with 20 the pans for re-use before the supports for the concrete work are removed. To this end I provide a plate or stirrup adapted to rest upon the top of the supporting joist and connect hangers thereto in such manner that 25 the hangers may readily be disengaged. To the hangers I connect brackets of a desired form so arranged that they may be readily disengaged from the hangers to permit removal of the pans. Thereafter the hangers 30 may be removed and employed in subsequent operations on the same building, nothing being left as a part of the original assembly except the plate on the top of the joist. Another advantage in the construction de- 35 scribed is that the brackets and hangers may be assembled in the desired relation before the hangers are connected to the plates on the top of the joist. This simplifies the matter of assembling and preparing for the 40 location of the form pans.

The invention will be more readily understood by reference to the accompanying drawing, wherein,

Fig. 1 is a sectional view through a slab 45 and pair of beams showing the manner of use of the device of my invention;

Fig. 2 is a side elevation partly in section, on the line 2-2 of Fig. 1; and,

Fig. 3 is a perspective view of the plate 50 or stirrup and one of the hangers which I employ.

In the drawings it will be seen that the forms are intended for use in molding a slab 10, and beams 11 of concrete. To this 55 end I employ sheet metal pans or forms 12, which serve to define the beams and the

bottom of the slab, the lower surface of the beams being determined by a plank 13. The plank is supported by joist 14.

The form pans rest upon and are securely held in position by means of brackets 15, which as shown, may consist of two pieces of metal suitably shaped and joined by rivets 16, the inner terminal portions of the sections of metal being spaced apart and shaped to form apertured ears 17, adapted to straddle a channel-shaped hanger 18, the flanges of which are provided with registering spaced apart apertures 19. A nail or pin 20, is employed for disengageably connecting the brackets to the hangers in a desired vertical position. The position of the hangers relative to the plank 13, determines the relative height of the pans and consequently the depth of the beams 11.

The hangers 18 are, at their upper ends, provided with a straight transverse pin 21, and a bent transverse pin 22, both of which are firmly fixed in position. The pin 21 is adapted to engage the hooks 23, formed in the downturned terminal portion 24 of a plate or stirrup 25. The hooks at each side are spaced apart by cutting out the metal of the down-turned portion 24 to permit the hangers to be accommodated therein. The bent pin 22 is so positioned that the hangers cannot rotate or swing on their pins 21, and by forming the pin 22 as shown, it is impossible for the workman to improperly associate or assemble the parts.

It will be noted that the brackets are provided with upstanding lugs or lips 26, which securely retain the lower edges of the pans in position. By employing brackets of greater or less width, the width of the beams may be controlled as desired.

After the parts have been assembled as shown and the concrete has been poured and suitably set, the nails 20 are removed in a convenient manner and the brackets 100 dropped. The pans may then be disconnected and thereafter the hangers may be disengaged from the stirrup by raising the same to a point permitting the disengagement of the pin and hook. The pans, 105 brackets and hangers may then be re-used. This effects a considerable saving in the quantity of material required for a single job and simplifies materially the matter of assembling and operation of the device as 110 a whole. Obviously those skilled in the art may effect a reversal of the construc-

tions shown and this, together with other modifications I consider to be within the scope of my invention.

I claim:

- 5 1. In a form support, the combination of a strap, hangers pivoted to said strap and provided with spaced apertures, and brackets adapted to be disengageably connected to said hangers and to support forms.
- 10 2. In a form supporting device, the combination of a strap, hangers adapted to be pivoted to the strap and to be readily disengaged therefrom, said hangers being provided with spaced vertical apertures, and
- 15 brackets adapted to engage said hangers by means of said apertures and to support forms.
- 20 3. In a form supporting device, the combination of a plate providing pivot recesses, hangers having parts adapted to engage said recesses, and brackets adapted to engage said hangers at different points in the length of the hangers and to support form pans.
- 25 4. In a device of the class described, the combination of a plate adapted to rest on the top of a supporting joist and provided with hooks on opposite sides thereof, hangers having cooperating hook elements at their upper ends for disengageable connection
- 30 with said plate, brackets, and means on the brackets and hangers for facilitating their disengageable cooperation.
- 35 5. In a device of the class described, the combination of a plate adapted to rest upon the top of a joist and provided with hooks at either side thereof, hangers provided with pins at their upper ends for engagement

with said hooks, form supporting brackets, and means on the brackets and hangers for effecting disengageable connection therebetween at different points in the length of the hangers.

6. In a form supporting device, the combination of a plate adapted to rest upon a support joist, said plate being provided with sides the terminal portions of which are bent into hook shape, hangers having portions at their upper ends adapted to engage said hooks and transversely apertured at different points in their length, and brackets for supporting forms, said brackets being adapted to be held in different vertical positions by cooperation with the apertures in said hangers.

7. In a form supporting device, the combination of a plate, hangers having pivotal engagement with said plate, brackets adapted to be adjustable and disengageably connected to said hangers, said brackets being provided with upstanding lugs adapted to position the form pans held thereby.

8. In a device of the class described, the combination of a plate having open-top recesses at either side thereof, hangers having projections adapted to enter said recesses, brackets removably connected to said hangers, and means in the connection between the hangers and plate for preventing the hangers from swinging after being connected to the plate.

Signed at Chicago, Illinois, this 17th day of December, 1921.

WILLIAM E. WHITE.
